GEORGE W. GRADER AND MATTHIAS H. BALDWIN, OF MEMPHIS,
TENNESSEE.

Letters Patent No. 64,094, dated April 23, 1867.

IMPROVED STREET PAVEMENT.

The Schedule referred to in these Letters Patent and making part of the same,

TO ALL WHOM IT MAY CONCERN:

Be it known that we, GEORGE W. GRADER and MATTHIAS H. BALDWIN, of Memphis, Shelby county, Tennessee, have invented a new and improved Street Pavement; and we do hereby declare that the following is a full, clear, and exact description thereof, which will enable others skilled in the art to make and use the same, reference being had to the accompanying drawings, forming part of this specification.

The object of this invention is to construct a pavement which is stronger and cheaper than any other now in use, and in which no depressions and uneven parts can be formed, as is the case with those now in use.

The invention consists in the use of a cast-iron framework, which is arranged so as to form a number of square or polygonal cells, in which cells wooden blocks are arranged. These blocks project above the iron framework, so that the latter does not come into direct contact with the vehicles, &c., and is consequently not so easily worn. The wood when worn can be easily removed and replaced by new blocks. In the annexed drawing our invention is illustrated—

Figure 1 being a cross-section of a street, which is provided with our improved pavement.

Figure 2 is a top view of some of the iron framework.

Figure 3 is a sectional view of part of the complete pavement; and

Figure 4 is a perspective view of the latter.

Similar letters of reference indicate corresponding parts.

A is a cast-iron framework, so made as to form square or polygonal cells *a a*, into which wooden blocks B of corresponding shape are inserted, said blocks resting on flanges *b b* formed at the bottom of the cells, (see fig. 3.) The framework is formed in sections, as shown, which sections can be interlocked in such a manner that no one section can settle or get out of line as long as it or the surrounding sections are not broken. For this purpose projecting flanges *c* are formed on every alternate corner of each section, fitting into a recess, *d*, under the corner in the opposite section, so that these flanges alternately completely interlock the different sections. The wooden blocks B are or may be made tapering at the top, and the spaces thus left between them filled with tar and gravel, or with any other suitable material. But, if desired, the block can be so arranged that no or almost no spaces are left between them. The blocks can be easily removed from the frame A, and replaced, if desired.

We claim as new, as far as our invention is now perfected—

Interlocking the sections of the frame A, by means of the protecting flanges *c* on every alternate corner of each section, fitting into a recess *b* under the corner of the opposite section, thereby preventing the pavement from settling or getting out of line, as herein shown and described.

The above specification of our invention signed by us this   day of   , 1867.

GEORGE W. GRADER,
M. H. BALDWIN.
